UNITED STATES PATENT OFFICE

ENRICO SILVESTRI, OF MILAN, ITALY

COLLAPSIBLE OR FOLDING SKI

Application filed September 14, 1929, Serial No. 392,652, and in Italy September 17, 1928.

The present invention relates to a ski type consisting of two halves hinged to one another in such a manner that one half can be folded over the other when the ski is not to be used, whereas they are fixed and locked on the extension of one another's longitudinal axis when the ski is in use.

The accompanying drawings illustrate two execution forms (by way of example only) of the collapsible ski according to the invention.

Fig. 1 is a longitudinal section of the center portion, at the hinged joint, of the ski according to the first execution form.

Fig. 2 is the corresponding plan.

Figures 3 and 4 are cross sections through 3-3 and 4-4 respectively in Fig. 1.

Fig. 5 is a part section, similar to that given in Fig. 1, of the ski according to the second execution form.

Fig. 6 is the corresponding plan, with the plate, on which the foot rests, removed.

Fig. 7 is a section through 7-7 in Fig. 6.

Fig. 8 is a plate to be fastened under the shoe.

According to the invention, one of the halves into which the ski is divided carries a metal box at its hinged end. This box embraces the upper face and sides of this ski half and extends past its end in order to form a similar seat for the other ski half.

In the construction shown by Figures 1-3, 1 and 1' are the two longitudinal halves of the wooden ski; 2 is a metal box, C-shaped in section, and attached upon the upper portion of the ski half 1, to which it is secured in any convenient manner, as, for example, by pins 31. The box 2 projects past the end of the ski half 1 which terminates at 34, where it is fitted with a cross member of cylindrical form, 4, intended to constitute one half of the hinge coupling 4-9.

The upper side of the box 2 is preferably fitted with strengthening ribs 5 and supplies the surface on which the foot rests. The box may be provided with any desired means for fastening it to the shoe; in the drawings two side wings 6 are shown for this purpose by way of example, each wing having screws 7

therein which engage an iron clamp secured to the shoe.

The upper face of the other ski half 1' is fitted with a metal plate 8 having at its forward end a hollow cross groove 9 in order to conform to the member 4 and form the other half of the hinge coupling.

The two ski halves 1 and 1' are connected with one another by two side links 10 pivotally secured at 11 to the upwardly directed wings 12 of the plate 8 of the ski half 1'; by means of elongated holes 13, the two links 10 are connected to the pin 14, arranged transversely of the box 2, on the other side of the hinge coupling 4-9, relative to the pivots 11.

The two ski halves 1 and 1' are locked in their aligned position by a lug 15 fixed to the plate 8 of the ski half 1', to which lug corresponds a hole in the turned extension 16 of the box 2. In the end space thus formed in the box 2 a bolt 17 is lodged; a spring 18 tends to engage the bolt in a notch of the lug 15, which bolt may be retracted against the action of the spring by knurled button 19.

In the position shown in Figures 1 and 2, the ski is mounted and its two halves 1 and 1' are rigidly held on the extension of the longitudinal axis of each other by the box 2 which embraces their adjacent ends on three sides.

In order to fold the ski it is sufficient to retract button 19 so that the bolt 17 is disengaged from the lug 15, which can now be separated from the box 2 together with the end of the ski half 1'.

Owing to the longitudinal motion allowed by the elongated holes 13 of the links 10, the contacting surfaces of the cross members 4 and 9 can be moved somewhat apart from each other and so the two halves 1 and 1' can be moved away from each other and remain interconnected by the links 10 alone.

In the construction illustrated by Figures 5 to 7 a metal box 2 is still provided, the box being fixed to the ski half 1 and its extended portion serving to receive the end of the ski half 1' as well as a lug 15 fixed to 1' and 100

engaging a hole in the box 2 where it is held by a bolt 17.

Instead, the connection between 1 and 1' is effected by links arranged inside of the box 2, viz. by two pairs of links 20, 21 hinged to each other at 22; the opposite ends of the links 20 are hinged to the box 2 at 23, whereas the free ends of the links 21 are interconnected by a cross member 24 inserted with a clearance in a member 25 secured to the ski half 1'.

The engagement between the halves 1 and 1' is further assisted by one or more pins 26 fixed at the end of one of them, for instance of 1, and adapted to enter the corresponding recesses provided in the adjacent end of the other half.

In this construction the engagement of 1 and 1' by means of pins like 26, and the flat form of the contacting surfaces of the two halves are rendered practicable by the longitudinal movement of which the two halves are susceptible relatively to each other due to the described connection.

In fact, once the bolt 17 has been released and the lug 15 has been removed from its seat, the ski half 1' can be moved axially away from the half 1 due to the clearance with which the cross member 24 is lodged in the member 25; after this the two halves 1 and 1' can be folded over each other.

In both constructions the box 2 and the other metal parts should preferably be made out of a metal possessing at the same time the necessary strength and the maximum lightness, such as very strong aluminium alloy.

Having now particularly described and ascertained the nature of my said invention and in what manner the same is to be performed, I declare that what I claim is:—

40 1. A collapsible ski, comprising two stick members, a metallic housing fastened to one end of one of said stick members, means for lodging one end of the other stick member in said housing, and means for retaining said stick members in longitudinal alignment.

45 2. A collapsible ski as claimed in claim 1, wherein the housing covers the stick members at the sides and top, and the top of which constitutes the foot rest.

50 3. A collapsible ski, comprising two stick members, a metallic housing fastened to one end of one of said stick members, means for lodging one end of the other stick member in said housing, a lug fixed to the top of said second stick member, a recess in said housing for receiving said lug, means attached to the housing for releasably engaging said lug to retain said stick members in longitudinal alignment.

55 4. A collapsible ski, comprising one stick member, a metallic housing fastened to said stick member and extending forwardly beyond one extremity thereof, said stick member terminating in a cylindrical form, a second stick member, one of whose extremities

is adapted to cooperate with the end of the first member to form a hinge joint, a pin extending across said housing rearwardly of said joint, link rods, with longitudinal slots at their rear, pivoted upon the front of each side of the second member, engaging said pin by means of said longitudinal slots therein, allowing a longitudinal movement between the stick members to uncouple the said hinge joint, and means for locking these members in position to prevent such uncoupling.

5. A collapsible ski, comprising a stick member, a metallic housing fastened to said member and extending forwardly beyond one extremity thereof, a link system contained in said housing, a second stick member movably engaging said link system, and means for releasably locking said stick members in longitudinal alignment.

6. A collapsible ski, comprising a stick member terminating in a square end, pins disposed in said end, a metallic housing fastened to said member and extending forwardly beyond said end, a link system contained in said housing, a second stick member movably engaging said link system, one extremity of said latter stick member terminating in a square end, recesses in said end adapted to cooperate with the pins in the end of the first stick member when the stick members are in longitudinal alignment, and means for releasably locking said stick members in said position.

7. A collapsible ski comprising two stick members, a metallic housing fastened to one end of one of said stick members, said end terminating in a shaped surface, means for seating one end of the other stick member in said housing, said latter end terminating in a second surface congruous to said first, and means for retaining said stick members in longitudinal alignment, with said surfaces abutting each other in said housing.

8. A collapsible ski comprising two stick members, a metallic housing fastened to one end of one of said stick members, said end terminating in a shaped surface, means for seating one end of the other stick member in said housing, said latter end terminating in a second surface congruous to said first, and connecting means between said housing and said second stick member for retaining said stick members in longitudinal alignment, with said surfaces abutting each other in said housing.

9. A collapsible ski comprising two stick members, a metallic housing fastened to one end of one of said stick members, said end terminating in a shaped lateral surface, a co-operating lateral surface at one end of the second stick member, means for seating said end of said second stick member in said housing at the three lateral edges of said end, and releasable locking means for retaining said stick members in longitudinal alignment.

with said second stick member seated in said housing.

10. A collapsible ski comprising two stick members, a metallic housing fastened to one end of one of said stick members, said end terminating in a shaped surface, a metallic fitting with a surface corresponding to said shaped surface mounted at one end of the second stick member, means for connecting said stick members with play, and means for seating said end of said second stick members in said housing with their surfaces abutting each other and retaining said stick members in longitudinal alignment.
15. Signed at Milan, Italy, this 6th day of September, 1929.
